(57) **CLAIM**

The ornamental design for a tripod for cameras as shown and described.

DESCRIPTION

FIG. 1 is a top view of the tripod for cameras of my design; FIG. 2 is a front left perspective view thereof;

FIG. 3 is a front right perspective view thereof;

FIG. 4 is a right-side view thereof;

FIG. 5 is a front view thereof;

FIG. 6 is a left-side view thereof;

FIG. 7 is a rear view thereof; and

FIG. 8 is a bottom view thereof;

FIG. 9 is a top view of the tripod for cameras of my design in a folded configuration;

FIG. 10 is a front left perspective view thereof;

FIG. 11 is a front right perspective view thereof;

FIG. 12 is a right-side view thereof;

FIG. 13 is a front view thereof;

FIG. 14 is a left-side view thereof;

FIG. 15 is a rear view thereof; and,

FIG. 16 is a bottom view thereof.

The broken lines shown are included for the purpose of illustrating portions of the tripod for cameras that form no part of the claimed design.

1 Claim, 16 Drawing Sheets
